Primary Examiner — Kevin K Rudzinski*Assistant Examiner* — Amber J Rabie(74) Attorney, Agent, or Firm — Banner & Witcoff, Ltd.(57) CLAIM

The ornamental design for a shoe, as shown and described.

DESCRIPTION

The sole FIGURE is a bottom view of a shoe showing my new design.

The broken lines immediately adjacent to the shaded area represent the bounds of the claimed design and form no part thereof. The broken lines depicting the remainder of the shoe form no part of the claimed design.

1 Claim, 1 Drawing Sheet
